UNITED STATES PATENT OFFICE

91,386

DESIGN FOR A CASE FOR AUTOMOBILE RADIOS

Earl C. Booth, Columbus, Ind., assignor to
Noblitt-Sparks Industries, Inc., Columbus,
Ind., a corporation of Indiana

Application May 12, 1933. Serial No. 48,086

Term of patent 7 years

To all whom it may concern:

Be it known that I, EARL C. BOOTH, a citizen of the United States, residing at Columbus, Bartholomew County, Indiana, have invented a new, original, and ornamental Design for a Case for Automobile Radios, of which the following is a specification, reference being had to the accompanying drawing, forming part thereof.

Figs. 1, 2, and 3 are front, side, and rear eleva-

tions respectively of a casing embodying my design.

I claim:

The ornamental design for a case for an automobile radio as shown.

In witness whereof, I have hereunto set my hand.

EARL C. BOOTH.
